UNITED STATES PATENT OFFICE.

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

CASE-SHIFT MECHANISM.

Application filed July 25, 1922. Serial No. 577,357.

To all whom it may concern:

Be it known that I, MANSFIELD C. CRAWLEY, a citizen of the United States, and a resident of Groton, in the county of Tompkins and State of New York, have invented certain new and useful Improvements in Case-Shift Mechanisms, of which the following is a specification.

The object of this invention is to provide a power-operated case-shift mechanism for typewriting machines. The embodiment of the invention illustrated is especially adapted for use in that type of machine illustrated in my former Patent No. 1,156,061, dated October 12, 1915, in which a continuously-running rotary motor is employed for operating the printing instrumentalities, the work of the operator being reduced simply to selecting the keys and lightly depressing them, the motor serving to supply all the power necessary for operating the type-bars. In the drawings I have shown a machine of this type provided with a case-shifting mechanism which utilizes the power of the motor to raise the case-shift frame or support (i. e., platen-support or the type-bar segment, as the case may be), the particular construction illustrated herein being especially adapted for that type of machine in which the platen is shifted up and down to obtain the case positions, as more fully hereinafter set forth.

In the drawings—

Fig. 1 is a vertical longitudinal sectional view of a typewriting machine embodying my mechanism, the parts being shown in upper-case position, having been put into action by the shift-key, i. e. temporary hold-up key;

Fig. 2 is a vertical section on the line 2—2 of Fig. 1, showing the parts in normal lower-case position;

Fig. 3 is a perspective view of some of the parts in detail, showing the parts in lower-case position;

Fig. 4 is a vertical sectional view showing the positions of the parts at the end of the downward movement of the shift and lock-up key on lever 25;

Fig. 4^a is a fragmentary sectional view showing the parts locked in upper case position after release of the shift and lock-up key;

Fig. 5 is a detached perspective view of some of the parts in the position they as-

sunie upon depression of the shift and lock-up lever 25;

Fig. 6 is a detail vertical sectional view of the friction-slip clutch;

Fig. 7 is a plan view showing more particularly the platen-support; 60

Fig. 8 is a vertical longitudinal sectional view through one of the platen-shaft housings, the platen being in lower-case position; 65

Fig. 9 is a transverse vertical sectional view taken centrally through Fig. 8;

Fig. 10 is a view similar to Fig. 8 showing the platen in upper-case position; and

Fig. 11 is a view similar to Fig. 5 showing the parts in the position they assume 70 upon depression of the temporary shift-lever 64.

Referring to the drawings annexed by reference-characters, the numeral 15 designates an electric motor affixed to the frame of the 75 machine at the rear thereof and adapted to drive a belt 16 which extends forwardly and engages a belt-wheel on a shaft 17 journaled in suitable bearings at the rear of the machine, whereby said shaft 17 may be continuously driven during the whole time the machine is in use.

A driving friction-clutch member (comprising a fiber disk 18 rigidly and non-rotatively held on shaft 17 by a pin 14 and 85 having its periphery tapered toward one end to form a conical friction surface) is adapted to be gripped by the outwardly flaring or conoidal flange 19^a formed on a disk-like metallic friction-clutch member 19 rotatively or loosely mounted on the shaft and adapted to be shifted longitudinally of the shaft. The driven member 19—19^a is adapted to be pressed against the driving member 18 by means of an upright resilient or 90 springy sheet metal lever 21 formed intermediate its ends with a laterally bent lug pivotally held by a pivot screw 13 to a bracket 29 secured to the machine frame. A pinion 26 is affixed to the driven clutch member 19, and a washer 20 is loosely mounted on shaft 17 between the outer end of said pinion and the forked upper end of lever 21. A forwardly extending lug 22 on the inner end of a lever 23 engages the inner 95 face of lever 21 at the lower end of said lever 21. Lever 23 is pivoted at 12 on a boss on the machine frame and the upturned rear end 24 of a shift and lock-up key lever 25 engages under the outer end of lever 23 100

105

110

so that when the key on lever 25 is depressed the forked upper end of clutch lever 21 will press washer 20, pinion 26 and clutch member 19-19^a toward clutch member 18. 5 Clutch lever 21, being resilient, ensures a proper engagement of the clutch members without straining the parts. Key lever 25 is pivoted intermediate its ends on a rod 11 in the machine frame. The flange 19^a of clutch member 19 is cut away or notched radially at intervals at 19^b to form a plurality of spaced gripping portions which will yieldingly grip the cone surface of member 18 and whose radial edges will act as scrapers 10 during relative rotation of the clutch member to scrape off oil and dirt that may collect on the friction face of the member 18 and might interfere with the quick, positive action of the clutch members if not removed. 15 The toothed pinion 26 affixed to the loose member 19 of the clutch is relatively long and in all positions of the clutch member 19 constantly engages a toothed segment 27 pivotally mounted at 10 on a forwardly-projecting ear 28 formed on the bracket 29 affixed to the frame of the machine, the depending end of this segment being bifurcated 20 to form a pair of separated stop-fingers 30 adapted to alternately abut opposite faces of a double-end or duplex stop or bumper 31 formed of rubber and supported stationarily between the fingers 30 by means of a laterally bent ear 32 formed on the forward end of an arm 32^a extending 25 forward from bracket 29, said ear being adjustable by bending it fore and aft of the machine to insure accurate arresting of the segment in its fore and aft swinging movements. Pivotally connected to the segment 30 near the upper end of the segment is a link 33 the forward end of which is pivotally connected to a lever 34. A crank shaft 39 extends transversely of the machine frame, said shaft being rockably supported on two 35 pivot screws 35 and 38 carried by stationary parts of the machine frame. Lever 34 is also pivotally supported at its upper end on the pivot screw 35 to swing fore and aft of the machine. Shaft 39 is preferably 40 made from a piece of sheet metal of channel form in cross-section, and is formed with a forwardly extending crank arm 40 at its inner end on which is journaled a short forwardly extending antifriction roller 41 45 in constant engagement with the under face of a rail 42 extending longitudinally of the platen carriage 86 and rigidly supported on the shift-frame or vertically movable platen support hereinafter described, said rail being in effect a part of the shift frame. Rock shaft 39 is formed at its outer end with a rearwardly extending crank arm 43 provided with an integral laterally bent depending stop lug 44 adapted to be normally 50 held in engagement with the rear edge of lever 34 by means of a relatively strong retractile spring 45. Stop 44 is adjustable by bending it fore and aft of the machine to vary the tension of spring 45. 55 With the foregoing mechanism, it will be observed that whenever the clutch members are forced together through the medium of lever 25 operated directly, or operated indirectly as hereinafter described, the lower end of lever 34 will be thrown forward by 70 the pinion 26, segment 27, and link 33, and the forward stop finger 30 will engage stop 31 and arrest the segment, pinion, and driven clutch member 19. Should the operator hold the operating key depressed after 75 the shifting action is completed the clutch member 18 will readily slip or rotate relatively to member 19 and thus avoid straining the parts or stalling the motor as the friction clutch members are yieldably held 80 in engagement by the resilient lever 21. The forward swinging of lever 34 will rock the shaft 39, through the medium of the strong coil spring 45 and crank arm 43 which is connected with the lever by said strong coil 85 spring, and throw arm 40 and roller 41 upward to elevate rail 42 and thus shift the platen 85 to upper-case position, the platen being guided and positively arrested in its upward movement by means hereinafter described. The shocks and jerks due to the sudden, practically instantaneous, shifting 90 of the platen and its support to upper-case position, as well as those due to the arresting of the same in upper-case position, will 95 be cushioned by means of spring 45, thus reducing noise, strain, wear, and vibration to a minimum. A retractile spring 46, 100 which connects arm 43 to the rear part of the machine frame, is put under tension by 105 the forward thrust of lever 34 under power of the constantly running motor-driven shaft 17 and serves to assist the action of gravity in promptly restoring the parts to normal when the platen elevating mechanism is released to permit the platen to return to its normal lower-case position. Spring 46 is substantially weaker than spring 45 so as not to interfere with the shaft-rocking 110 and shock-absorbing functions of said 115 spring 45. 120 A latch 36 is pivoted at 9 on the lower free end of lever 34 to rock up and down, said latch extending rearwardly beyond a stationary transverse bar 37 in the machine frame and adapted to ride over the upper edge of said bar and drop down in front of the bar when lever 34 is swung forward. A spring 8 normally urges the rear end or nose of the latch downward in position to ride 125 up over bar 37 as the lever 34 swings forwardly and then snap down in front of the bar said spring normally holding the angular forward arm or end of the latch lever 36 against a limiting stop face or shoulder 7 130

formed on the forward edge of the fore and aft swinging lever 34.

A transversely extending flat spring or resilient plate 47 is secured at its inner end 5 to the front face of frame bar 37 and has its outer free end normally slightly bowed or curved forwardly away from the front face of said bar so as to have a limited movement fore and aft of the machine, said 10 spring being provided with a supporting and guiding ear 48 extending rearwardly upon the upper edge of bar 37 directly under latch 36. Spring plate 47 is formed with an angular forwardly extending arm 49 at 15 its free end, the depending portion of which carries an integral outwardly extending finger 50 normally engaging the forward edge of an upstanding hook 52.

Hook 52 is pivoted at its lower end at 20 52^a on the shift and lock-up key-lever 25 to swing fore and aft of the machine. The hook 52 is provided with an upwardly facing shoulder 53 at its rear edge which, during upward movement of hook 52 by the 25 upward movement of the rear end of lever 25 as hereinafter described, is adapted to engage under an outwardly extending finger 54 carried by an upstanding latch-releasing plate 55 and rock said plate. The extension 30 81 of the latch releasing plate 55 is normally immediately in front of lug 48 in the path of the rear arm of the latch lever 36, and the lower end of said plate is pivotally supported at 82 on the transverse bar 35 56 of a U-shaped bail. The forwardly extending arms 57 of the bail are pivotally held to a transverse rod 58 mounted in the machine frame on brackets 58^a to permit the bail to rock up and down in the frame. The 40 laterally swinging plate 55 is yieldably held in normal position by a spring 59 which connects the outwardly extending finger 54 on said plate with a horizontal extension or outwardly projecting finger 60 formed 45 on the left hand end of the bail bar 56. Plate 55 is provided with a pair of oppositely extending stop fingers 61 adapted to engage the top edge of the bail bar 56 to limit the rocking movements of plate 55 in 50 opposite directions, the spring 59 serving to normally tilt the plate toward the left hand side of the machine. The extension 60 of the bail engages under a downwardly facing shoulder 62 formed on the forward 55 edge of hook 52, this shoulder normally resting on the top edge of said extension 60 and hook 52 being normally pulled forward against the rear face of finger 50 on plate 47 to hold shoulder 62 over extension 60 by a 60 retractile spring 63 connecting finger 51 on the hook with the key lever 25. The bail 56 is adapted to be rocked upwardly by either of two key levers 64 pivotally supported intermediate their ends adjacent opposite sides of the machine on fulcrum rod 65 and provided with inwardly extending lugs 83 at their rear ends engaging under the side arms 57 of the bail. Key levers 64 serve as "temporary shift" key levers and also as unlocking or releasing key levers 70 for restoring the parts to normal position after a shift and lock-up operation brought about by direct action of key lever 25, as hereinafter described.

Key-controlled power mechanism embodying the present invention may be employed in connection with various known types of case-shifting operations, for example, to shift a platen and its carriage and bed bodily, to shift a movable platen 80 support or shift frame relatively to the carriage, to shift a type segment or support directly, or to shift a movable frame or support upon which a type segment or other mounting for type-bars or type-carrying means is held. In the type-bar shift style of case-changing the type-bar segment itself sometimes constitutes the shiftable support or frame which is moved to vary the relation between the type-bars and platen to change case. In the embodiment of the invention illustrated, a specially constructed shift frame or platen support is mounted in the platen carriage to move up and down to change case, but it will be understood that the invention may be embodied in case-shifting mechanisms of other types as above stated.

In the construction shown, the shaft 84 of the platen roll 85 is journaled in a pair 100 of side plates 65 of the shift frame, each of which plates is supported on the forward ends of a pair of superposed parallel links 67. The two pairs of superposed links 67 are located inside the opposite side rails of 105 the platen carriage frame 86 and the two uppermost links are rigidly connected at their rear ends by a sleeve 87 rotatably supported on the upper one of two rods 88. The ends of pivot rods 88 extend through 110 the depending flanges or side webs 66 and 69 of the channel side rails of the carriage and are held in place by lock nuts 89 threaded on the rods. Screws 90 pivotally connect the forward ends of the links 67 with the 115 side plates 65 of the shift frame. The two lower links are pivotally held to the lower rod 88, and rail 42, before described, is rigidly affixed at its ends to said two lower links 67 intermediate the ends of said links. 120 A brace plate 70 is riveted to the under side of the top web of each channel side rail of carriage 86, said plates being bent downward to provide clearance for the platen shaft and serving to stiffen the channel or 125 flanged side rails. The flanges 66 and 69 of each side rail are provided with registering slightly arcuate slots 68 in which the platen shaft 84 is substantially vertically movable when rail 42 of the shift 130

frame is raised and lowered during the case-shifting operations.

The upper-case position of the platen is determined by adjustable stop screws 71 which extend downwardly through registering apertures in the side rails of the carriage and reinforcing plates 91 held to the tops of the side rails by screws 74. The platen is arrested in lower-case position by adjustable stop screws 72 which extend upwardly through apertures in the downwardly bent portions of the braces 70. The stop screws 71 are adjustably mounted on the free rear ends of strong or stiff flat springs or resilient bumper plates 73 each of which is held on top of one of the plates 91 by one of the screws 74. The lower stop screws are adjustably mounted on strong or stiff spring bumper plates 75 each of which is held by screws 92 at its forward end to an extension 76 of plate 70. The spring bumpers 73 and 75 are sufficiently resilient to momentarily flex slightly and thus deaden the noise of impact of shaft 84 on the stop screws and absorb vibration but are made relatively stiff and stronger than spring 45 so that they will instantly return to normal position after impact of the shaft on the screws carried thereby so that the platen will instantly come to rest at the desired case-shift position when moved either up or down. To resist any tendency of the platen and shift frame to rebound at the end of its sudden up and down shifting movements, lugs 77 are provided on the lower links 67 of the shift frame and are adapted to ride over bosses or lumps 78 formed on the depending fore and aft flexible rear end portions 79 of spring bumpers 75, parts 78 and 79 forming resilient detent devices for the shift frame at each side of said frame adapted to yieldably hold the platen shaft against either stop screw. The detent devices are not strong enough to interfere with the upward movement of the shift frame and platen by power or its downward movement by spring 46 and the action of gravity when the mechanism is released to permit the platen to return to normal lower-case position. To counterbalance the weight of the shift frame and parts supported thereon and assist in cushioning the downward movement of said frame and the platen, the detent lugs 77 on the shift frame are connected to plates 70 on the carriage frame 86 by light retractile counterbalancing springs 80. The key levers 25 and 64 are restored by suitable compression springs 93. The carriage 86 is supported to travel transversely of the machine frame 94 on suitable antifriction bearings 95.

Shift and lock-up operation.

When it is desired to write a number of upper-case characters, the operator depresses and immediately releases the key on

the key-lever 25. When said key is depressed hook 52 on lever 25 is lifted, causing shoulder 53 on the hook to engage under finger 54 on the latch-releasing plate 55 and move the plate laterally inward and thus move its highest part or extension 81 out of the path of latch 36 and the point on the front face of spring 47 which the nose or rear end of the latch is adapted to engage when lever 34 is swung forward. At the same time, extension 24 of lever 25 is raised and rocks the downwardly extending inner arm of the bell-crank lever 23 to cause lug 22 thereon to press outwardly on the lower end of clutch lever 21, thus rocking the upper end of said resilient lever 21 inwardly or toward the right and forcing clutch member 19-19^a against clutch member 18 under spring pressure. This causes member 19 and pinion 26 to rotate rapidly in the direction indicated by the arrow on the drawing (Fig. 4^a) and rock segment 27 and lever 34 from the positions shown in Fig. 3 to those shown in Fig. 4, the latch 36 riding over lug 48 and being snapped down in front of the forwardly bowed portion of spring plate 47 by spring 8. The forward thrust of lever 34 exerts a pull on the resilient connection 45 between said lever and arm 43 of rock shaft 39 which rocks the shaft in a direction to throw arm 40 and its roller 41 upward, thus throwing up the shift frame and platen until the platen shaft 84 strikes the stop screws 71 which yield slightly and instantly return to their normal position and hold the platen in its upper-case position. Spring 45 absorbs shocks and jerks and also permits slight relative movements between lever 34 and lug 44 on the arm 43 of the rock-shaft, said lever moving away from said lug slightly when thrust forward, as shown in Fig. 4. As soon as pressure on the key on lever 25 is relieved the pressure on clutch member 19-19^a is relieved and the driving connection between the power shaft and said clutch member is broken permitting spring 45 to contract slightly and draw lever 34 slightly rearward toward or against stop 44 and move latch 36 slightly rearward until its rear end presses spring plate 47 against bar 37, as shown in Fig. 4^a, thus locking the platen-lifting mechanism against return movement while permitting key lever 25 to return to normal position and leaving both hands of the operator free to actuate printing keys to write upper-case characters. Bar 37 forms a fixed abutment for the latch. The latch drops down directly over a shoulder 65 on release plate 55 and said plate is held in its inwardly rocked position by the engagement of the outer edge of extension 81 with the inner side face of the latch, as shown in Figs. 4 and 4^a. The rearward flexing of spring plate 47 by the latch causes finger 50 on arm 49 of said plate

to rock and hold the pivoted hook 52 rearward far enough for shoulder 62 on the hook to be out of the path of movement of finger 60 on bail 56, thus breaking the normal lifting connection between the bail and key lever 25 after a direct operation of said key lever by its own key, as shown in Fig. 4.

Release after shift and lock-up.

- 10 When it is desired to again write in lower-case after a shift and lock-up operation, the operator depresses and immediately releases either of the keys on key-levers 64, thus causing bail 56 to move upward and return to normal position. As the connection between hook 52 and the bail is at this time broken as above described, the operation of key-lever 64 will not move key-lever 25 and, as there is no connection between either of 15 the key-levers 64 or the bail and the clutch-operating means, the platen-shifting parts will not be connected with the motor on depression of the key on either lever 64. The upward movement of the bail lifts the 20 latch-release plate 55 and causes shoulder 65 on said plate to rock the nose of the latch 36 upward far enough to clear flat spring 47 and bar 37 whereupon springs 46 and 45 will rock the shaft 39, lever 34, link 33, segment 25 37 and latch 36 to their normal positions shown in Fig. 3 and the platen and shift frame will be returned to normal lower-case 30 position by gravity, the rail 42 dropping as roller 41 is drawn quickly downward. The 35 disengagement of latch 36 from in front of spring 47 allows the outer end of said spring to swing forward to its normal position so that its finger 50 moves forward and permits spring 63 to snap shoulder 62 on hook 52 over bail finger 60 when the bail moves back down to its normal position on release of key lever 64, thus restoring the lift-up connection between the bail and key-lever 25. The 40 disengagement and return of the latch also permits plate 55 to rock back to its normal position with extension 81 again in the path of forward movement of the latch.

Temporary shift operation,

- 45 When it is desired to shift and hold the platen up temporarily, for writing one or a very few upper-case characters, the operator depresses and holds down the key on either of the key-levers 64, thus rocking bail bar 56 upward and holding it elevated. The upward movement of the bail causes finger 60 to pull hook 52 upward thus actuating lever 25 indirectly, as shown in Fig. 1, to rock the rear end 24 thereof upward and hold it 55 raised. The clutch is thrown in and the platen elevated in the same manner as when lever 25 is directly operated, but as release plate 55 moves up with the hook 52 and the bail, said plate will not be rocked by shoulder 53 on the hook 52, and extension 81

remains in the path of latch 36 and swings said latch up and holds it, as shown in Fig. 1, so that plate 47 is not moved back to disengage hook 52 from the bail and latch 36 is also held in an ineffective position. The 70 clutch members are thus held in engagement as long as the operator holds down the key on key-lever 64. The driving member 18 of the clutch is free to slip or rotate relatively to the driven clutch member 19, however, and 75 thus holds the platen up but without injurious strain on the parts and without stalling the motor. Upon release of the depressed key on lever 64 the clutch will be released and the parts will be instantly restored to normal position shown in Fig. 3, the extension 81 on plate 55 holding latch 36 in position to clear bar 37 as lever 34 swings rearward.

A stop lug 96 on the upper edge of key lever 25 is adapted to engage a stop 97 held to a key-lever glide-comb 98 mounted in the machine frame, and thus limits the upward movement of key lever 25 to prevent excessive pressure on clutch lever 21. As key 90 levers 64 are not provided with stop lugs, said levers may move slightly farther than lever 25, when actuated as release levers after a lock-up operation, thus lifting plate 55 high enough for shoulder 65 to force latch 95 36 clear of bar 37 before levers 64 engage stop bar 97.

This application is a substitute in part for my co-pending applications Serial No. 188,771, filed August 29, 1917, and Serial No. 100 316,649, filed August 11, 1919.

What I claim is:

1. A typewriting machine comprising a constantly-operating drive-shaft, a case-shift-support, means adapted to be operated 105 through said drive-shaft for shifting the case-shift-support to its upper-case position, and key-actuated means for connecting said shifting means to the drive-shaft.

2. A typewriting machine comprising a 110 constantly-operating drive-shaft, a case-shift-support, means adapted to be operated through said drive-shaft for shifting the case-shift-support to its upper-case position, key-actuated means for connecting said 115 shifting means to the drive-shaft, and means to lock the case-shift-support in its upper-case position.

3. A typewriting machine comprising a 120 constantly-operating drive-shaft, a case-shift-support, means adapted to be operated through said drive-shaft for shifting the case-shift-support to its upper-case position, key-actuated means for connecting said 125 shifting means to the drive-shaft, means to lock the case-shift-support in its upper-case position, and additional key actuated means for releasing the case-shift-support from its upper-case position.

4. A typewriting machine comprising a 130

- constantly-rotating drive-shaft, a case-shift-support, means adapted to be operated through said drive-shaft for shifting the case-shift-support to its upper-case position, and key-actuated means for connecting said shifting means to the drive-shaft.
5. In a typewriting machine, power-driven means for case-shifting embodying a constantly-rotating shaft and a crank rock-shaft capable of alternately rocking in opposite directions, the power from said constantly-rotating shaft serving to rock it in one direction to make the case shift to the up-position, means being provided for locking the parts in the up-position, and key-controlled devices for putting the power-means into action and also for releasing the lock-up means to permit a down-shift to take place, said power-driven means also embodying a pair of constantly-meshing toothed elements one being a pinion attached to one of said shafts and the other being a reciprocating element.
6. In a typewriting machine, power-driven means for case-shifting embodying a crank rock-shaft capable of alternately rocking in opposite directions, the power-means serving to rock it in one direction to make the cases shift to the up-position, means being provided for locking the parts in the up-position, and key-controlled devices capable of putting the power-means into action and devices for releasing the lock-up devices to permit a down-shift to take place.
7. In a typewriting machine, a power-operated case-shift mechanism embodying a slip-clutch under control of one of the key-levers.
8. In a typewriting machine, a motor driving a continuously-rotated shaft, and a case-shifting mechanism actuated from said shaft, said shifting mechanism embodying a slip-clutch controlled by a key-actuated lever.
9. In a typewriting machine, a motor driving a continuously-rotated shaft, and a case-shifting mechanism actuated from said shaft, said mechanism embodying a friction-slip clutch, a pair of key-levers, and means whereby the operation of either lever will put the clutch in operation.
10. In a typewriting machine, a motor driving a continuously-rotated shaft, and a case-shifting mechanism actuated from said shaft, said mechanism embodying a slip-clutch and key-controlled devices for putting the clutch into operation, these devices embodying a resilient clutch-shifting member adapted to ensure the clutch being resiliently pressed into action.
11. In a typewriting machine, a case-shifting means, a power-driven mechanism for actuating said case-shifting means embodying a friction slip-clutch, key-con-
- trolled devices whereby depression of a key will by manual force bring and hold the friction members of the clutch into contact, means for holding the case-shifting mechanism in its shifted position, and another key mechanism for releasing the said holding mechanism.
12. In a typewriting machine, a power-operated case-shift mechanism embodying a key-operated clutch having a driving member adapted to rotate relatively to a rotary driven member irrespective of the position of the operating key after the case-shift movement is completed.
13. Power-operated case-shift mechanism comprising a shift-frame movable to vary the relation between printing instrumentalities and a platen, a constantly-rotating power-shaft, a clutch-member held to the shaft to rotate therewith, a second clutch-member loose on the shaft, means connecting the loose clutch-member with the shift-frame for shifting the frame, a key, and means operated by the key for forcing the clutch-members into driving engagement, the first clutch-member being free to rotate relatively to the loose clutch-member irrespective of the position of the key after the shift-frame reaches its shifted position.
14. In a typewriting machine, a continuously-driven shaft, a case-shifting mechanism embodying a friction clutch and a stop, manually-operable means capable of putting the clutch members into engagement and holding them in engagement to thereby cause said mechanism to shift the case-shift support, the clutch being adapted to slip to thereby permit the shifting mechanism to be arrested without stopping the running of the shaft should the operator maintain force on the manually-operable means after the shifting mechanism is arrested by said stop.
15. In a typewriting machine, a power-driven case-shift embodying a key-controlled slip-clutch, a pinion connected to the clutch, and a segment in constant engagement with said pinion.
16. In a typewriting machine, a power-driven case-shift embodying a key-controlled slip-clutch, a pinion connected to the clutch, a segment in constant engagement with said pinion, and devices for limiting the movement of the shift mechanism by limiting the movement of said segment.
17. In a typewriting machine, a continuously-driven shaft, a slip-clutch thereon and key-controlled means for putting this clutch into action, a case-shift mechanism and means for driving it from said clutch comprising a pinion and segment, means for arresting the movement of the segment, and a pitman connecting the segment to said mechanism.
18. In a typewriting machine, a power-driven case-shift mechanism embodying a

- spring and means for tensioning the spring when the mechanism is shifted out of normal, whereby the tensioning of said spring is utilized to assist in returning the parts to normal when released.
19. In a typewriting machine, a power-driven case-shift mechanism, key-controlled devices for connecting the power thereto to cause an operation, an automatic latch to hold the parts in their power-shifted position, another key-controlled means for releasing said latch, and a spring for returning the case-shifting mechanism to normal when thus released.
- 15 20. In a typewriting machine, a power-driven case-shift mechanism embodying a friction-slip device for connecting the power to said mechanism, a first key-lever and means operated thereby for putting said device into action, an automatic device for locking the mechanism when thus shifted, a second key-lever means operated thereby for releasing said automatic device on the down stroke of the key-end of the lever to permit restoration of the shifting mechanism to normal, and additional means whereby said second lever may be operated in the first instance to cause a case-shift action.
21. In a typewriting machine, a power-driven case-shift mechanism, a first key-lever and means operated thereby for connecting the power to said mechanism, a latch device for locking the case-shift mechanism in shifted position, a second key-lever and means whereby this second key-lever may be operated to release said latch on the down stroke of its key-end if the case-shift mechanism is already shifted or put the case-shift mechanism into action if it has not been previously shifted through the medium of said first key-lever.
22. In a typewriting machine, a power-driven case-shift mechanism, a first key-lever for connecting the power to said mechanism to shift the same, an automatic latch to lock the shift mechanism in shifted position, a second key-lever for releasing said latch when thus previously put in latching position, and means whereby this second key-lever is normally connected up to said first key-lever before said first key-lever is operated, whereby said first key-lever may be operated through the medium of said second key-lever.
- 55 23. In a typewriting machine, a power-driven case-shift mechanism, a first key-lever and means operated thereby for applying the power to the case-shift mechanism, a latching device for automatically locking the case-shift mechanism when thus shifted, a second key-lever and a latching mechanism normally connecting it to said first key-lever, and means whereby this latching mechanism is released when the case-shift mechanism is put into operation by said first key-lever.
24. In a typewriting machine, a source of power, a power-driven case-shift mechanism, mechanism for connecting the same to the source of power, a pair of shift-controlling key levers, and means whereby one of said key-levers will actuate said connecting mechanism through the medium of the other lever.
25. In a typewriting machine, a source of power, a power-driven case-shift mechanism, mechanism for connecting said source of power with said case-shift mechanism to cause a case-shift operation thereof, said case-shift mechanism embodying means for automatically latching the case-shift mechanism in its shifted position, latch-releasing means, a first lever for actuating the power-connecting means and a second lever for actuating said latch-releasing means, means whereby said first lever for releasing the latch may be operated alone or through the medium of the second lever, and means automatically operated by a part of the case-shift mechanism to permit operation of the second lever independently of the first lever after a change of case by an operation of the first lever alone.
26. In a typewriting machine, a source of power, a power-driven case-shift mechanism, a first key-lever for connecting the source of power to said mechanism to shift the same, an automatic latch to lock the shift mechanism in shifted position, a second key-lever for releasing said latch when thus previously put in latching position, and means connecting this second key-lever to said first key-lever when said key-levers are in normal position, whereby said first key-lever may be operated through the medium of said second key-lever, said means consisting of a spring-actuated latch carried by the first key-lever.
27. In a typewriting machine, a source of power, a power-driven case-shift mechanism, a first key-lever and means operated thereby for applying power from said source of power to the case-shift mechanism, a device for automatically locking the case-shift mechanism when thus shifted, a second key-lever, a latch carried by one of the levers normally connecting the two levers, and means whereby this latch is released only when the case-shift mechanism is put into operation by said first key-lever.
28. In a typewriting machine, a power-driven case-shift mechanism and key-controlled mechanism for putting the same into action, said case-shift mechanism embodying a latch for holding it in its shifted position, said key-controlled mechanism embodying a key-lever for putting the power mechanism into action directly, a second key-lever, a gravitating bail actuated thereby and adapt-

ed to operate to release said latch, and means for normally connecting said first lever with said second lever and its bail, for the purpose set forth.

29. The combination with a typewriting machine, of case-shift mechanism comprising a shift-support, means for moving said support away from its normal case position, a constantly-driven power-shaft, a vertically-shiftable member extending transversely of the machine, a pair of key-levers located at opposite sides of the machine each of which is adapted to shift said member upwardly independently of the other, and means operable by said member for connecting the support-moving means with the power-shaft.
30. The combination with a typewriting machine, of case-shift mechanism comprising a shift-support, means for moving said support away from its normal case position, a constantly-driven power-shaft, a vertically-shiftable member extending transversely of the machine, a pair of key-levers located at opposite sides of the machine each of which is adapted to shift said member upwardly independently of the other, and means operable by said member for connecting the support-moving means with the power-shaft, and a third key-lever adapted to operate said connecting means independently of said vertically-shiftable member.

31. In a typewriting machine, a shift-frame, power-operated mechanism for shifting said shift-frame, two key-levers and means whereby the operation of either will put said mechanism into action to cause a case-shifting operation, said means embodying a lever-latch, normally connecting the levers, an automatic latch capable of locking said mechanism in shifted position, means whereby when one of said key-levers is actuated the latch will be prevented from operating and whereby when the other lever is operated the latch will be permitted to come into action, and a spring-member actuated by said latch when it comes into action to disconnect said lever-latch to thereby render the key-levers independently operable.

32. In a typewriting machine, a power-driven case-shift mechanism, a first key-lever and means actuated thereby for connecting the power mechanism with the case-shift mechanism to cause a shifting action, an automatic holding-device for locking the parts in their shifted position, and a second key-lever mechanism for releasing said holding-device on the down stroke of the key-end of the lever whereby a quick return of the shifting mechanism to normal is assured whether or not the operator continues to press the key-end of said second key-lever.

33. In a typewriting machine, a shift-frame and key-controlled power mechanism

for moving said shift-frame to its up position, stops for arresting the upward movement of the shift-frame, said power mechanism embodying an elastic cushioning device brought into action when the frame is upwardly shifted against said stops.

34. In a typewriting machine, a shift-frame, key-controlled power mechanism for shifting said shift-frame, stops for arresting the upward movement of the shift-frame, said mechanism embodying a rockable member adapted to engage the shift-frame, a lever actuated by power, and a resilient cushioning connecting means between the lever and said rockable member adapted to yield when the shift-frame is thrown upwardly against said stops.

35. In a typewriting machine, a shift-frame, stops for arresting its upward movement, and key-controlled power mechanism for upwardly shifting said shift-frame, said mechanism embodying a rockable member having an arm adapted to engage the shift-frame and also having another arm, a pivotally-depending lever adapted to be swung by the power, and a contractile spring connecting said lever to said other arm, for the purpose set forth.

36. In a typewriting machine, a shift-frame and key-controlled power-operated mechanism for shifting said shift-frame embodying a pivotally-depending lever adapted to have its lower end swung fore and aft by the power, said lower end being provided with an automatically-acting latch adapted to hold the shift-frame in its up position, and key-controlled means for releasing said latch.

37. In a typewriting machine, a power-operated mechanism for changing case, key-controlled means for putting said mechanism into operation embodying a friction slip clutch consisting of two members one of which is constructed of separated portions adapted to frictionally engage the other member and having edges adapted to clean the friction surface thereof.

38. In a typewriting machine, a power-operated mechanism for changing case, key-controlled means for putting said mechanism into operation embodying a friction slip clutch consisting of two members, one of which is constructed of separated portions adapted to frictionally engage the other member and having radial scraping edges adapted to clean the friction surface thereof.

39. In a typewriting machine, a shift-frame, key-controlled power-operated mechanism for shifting said shift-frame, stops for arresting the movement of said shift-frame, said stops being resiliently mounted for the purpose of cushioning the arresting of the shift-frame, said stops consisting of

adjustable screws carried at the free-ends of flat springs.

40. In a typewriting machine, a platen shift-frame movable up and down, stops on the carriage adapted to engage the shaft of the platen and arrest its upward movement when shifted to upper-case, said stops being adjustably mounted on flat springs afixled to the carriage, and key-controlled power means for shifting the shift-frame upwardly until the platen-shaft strikes said stops.

41. In a typewriting machine, a shift-frame and key-controlled power-operated mechanism for shifting it upwardly to upper-case position and constructed to permit the shift-frame to drop to lower-case position by gravity, and a spring detent device for yieldingly holding the shift-frame 20 in either of its positions.

42. In a typewriting machine, power-operated means for case-shifting embodying an automatic latch for latching the parts in up position, two key-levers and means whereby the operation of either will put the shifting mechanism into action, and means actuated by one of said levers for preventing the latch from assuming latching-position.

43. In a typewriting machine, a shift-frame, power-operated mechanism for shifting said shift-frame, two key-levers and means whereby the operation of either will put said mechanism into action to cause a case-shifting operation, an automatic latch 35 capable of locking the mechanism in shifted position, and means whereby when one of said key-levers is actuated the latch will be prevented from operating and whereby when

the other lever is operated the latch will be permitted to come into action. 40

44. In a typewriting machine, a power-operated case-shifting mechanism embodying a latch capable of automatic action, two key-levers and means whereby the operation of either will put said mechanism into action 45 to change case, a latch-operating member and means whereby the actuation of one of said key-levers will shift said member to prevent latching and whereby actuation of the other lever will shift said guard to permit latching. 50

45. In a typewriting machine, a power-operated mechanism for changing case embodying a latch, two key-levers and means whereby the operation of either will put 55 said mechanism into operation to change case, a device capable of preventing the latch acting and also capable of permitting it to come into latching position and to also act to release the latch, and means whereby 60 said device may be actuated through said two key-levers.

46. In a typewriting machine, a power-operated case-shift mechanism embodying a latch capable of automatic action, two key-levers and means whereby the operation of either will put said mechanism into action 65 to change case, and a latch-actuating device consisting of an upstanding member adapted to be laterally tilted and having a shoul- 70 dered upper end adapted to engage the latch in the manner set forth.

In testimony whereof I hereunto affix my signature.

MANSFIELD C. CRAWLEY.

Certificate of Correction.

It is hereby certified that in Letters Patent No. 1,455,109, granted May 15, 1923, upon the application of Mansfield C. Crawley, of Groton, New York, for an improvement in "Case-Shift Mechanisms," errors appear in the printed specification requiring correction as follows: Page 4, line 48, for the misspelled word "platent" read *platen*; same page, line 69, strike out the word "and"; page 7, lines 86 and 87, claim 25, strike out the words "for releasing the latch" and insert the same to follow the word "lever", second occurrence, in line 91; and that the said Letters Patent should be read with these corrections therein that the same may conform to the record of the case in the Patent Office.

Signed and sealed this 12th day of February, A. D., 1924.

[SEAL.]

KARL FENNING,
Acting Commissioner of Patents.
